DESCRIPTION

FIG. 1 is a perspective view of the prosthetic device with a retaining strap according to the present invention;

FIG. 2 is an end elevational view of the prosthetic device with a retaining strap according to the present invention;

FIG. 3 is an opposite end elevational view of the prosthetic device with a retaining strap, meaning that FIG. 3 depicts the opposite end from that depicted in FIG. 2;

FIG. 4 is a side elevational view of the prosthetic device with a retaining strap;

FIG. 5 is an opposite side elevational view of the prosthetic device with a retaining strap, meaning that FIG. 5 depicts the side opposite to that shown in FIG. 4;

FIG. 6 is a top plan view of the prosthetic device with a retaining strap; and,

FIG. 7 is a bottom plan view of the prosthetic device with a retaining strap.
